UNITED STATES PATENT OFFICE.

JOHN HENRY VAILE AND HARRY F. BOE, OF DAYTON, OHIO.

PUMPING APPARATUS.

Application filed November 2, 1917. Serial No. 199,822.

To all whom it may concern:

Be it known that we, JOHN HENRY VAILE and HARRY F. BOE, citizens of the United States, and residing at Dayton, in the county 5 of Montgomery and State of Ohio, have invented a new and useful Improvement in Pumping Apparatus, of which the following specification is a full disclosure.

The invention relates to a water pumping apparatus particularly adapted for use 10 in connection with domestic water supply systems.

In commercializing domestic water supply systems it has been experienced that 15 laymen in making installations fail to recognize the importance of following definite instructions for setting up the apparatus accompanying each shipment, thus making faulty and improper connections to the disadvantage of the equipment. Frequent 20 source of trouble is due to faulty and improperly made connections in the suction line from the pump to the source of water supply, a leak in the suction line will permit 25 the priming water in the line to readily drain therefrom, resulting in the pump working idly without lifting water.

An object of the invention therefore is to 30 unitarily combine a pump and priming reservoir for constantly maintaining a priming charge of water within the pump to a definite water level height which may submerge the suction valve of the pump or flooding the parts controlled by said valve, 35 to reduce the possibilities of inaccurate and imperfect connection in making installations, with a more complete combining and assembling of the various parts and devices at the place of manufacture resulting in a 40 reduction of the cost of manufacture, and issuing a more efficient working of the system when installed.

Further objects and features of the invention are more fully revealed in the following 45 description of the accompanying drawings forming a part hereof, and in the drawings like characters of reference denote corresponding parts throughout the several views, of which:

50 Figure 1 is a central vertical section through the pump.

Figure 2 is a section on line 2—2, Figure 1.

55 Figure 3 is a section on line 3—3, Figure 2.

Figure 4 is a top plan view of the pump.

The pump is illustrated as of single piston type, although it could be constituted as of duplex type as far as the features of the invention are concerned. In detail 60 as to certain of its working parts it may follow well known pump principles of construction, for either single or duplex types.

The pump is especially adaptable for domestic water supply systems, of an automatically operated class, wherein the water of a relatively static source of supply is delivered by the pump to a compression tank, as a reserve or storage supply under pressure, converting the static water in the tank 70 to dynamic form at the fixtures or places of utilization. The pump is operated by power transmission devices under automatic control and the operation governed by a determined pressure influence in the rise and fall 75 of the pressure in the compression tank, whereby the pump is started when the pressure falls to a certain degree and continues until the pressure has been raised to a certain degree. It can therefore be recognized 80 that should the priming water in the suction end or line of the pump be accidentally drained as by reason of a leak through the connections, that the pump would operate idly without replenishing the water supply 85 to the system when the pressure in the system reached its low stage, and the pump in many cases would continue to so operate as it would be incapable of self priming. The water supply of the system could thus be 90 readily exhausted, necessitating repriming of the pump by an attendant.

This invention overcomes such conditions, as it provides a trap reservoir integrally combined with the pump for constantly 95 maintaining a pump priming charge of water not liable to accidental draining as the parts of the structure are properly and securely assembled at the place of manufacture.

100 Referring to the drawings, 1 indicates a casing having base webs 2 cast integrally with and extending from the lower portion of the casing to provide a support therefor. The casing interiorly is subdivided into 105 chambers by partition walls providing a pump inlet chamber 3, front and rear suction chambers 4—4 and a main water inlet chamber 5. The inlet chamber 5 is formed by the partition walls or vertical and horizontal webs 6—7 respectively and an offset 110 casing portion 8 projecting from one side

and at one end of the casing 1. The offset casing portion 8 vertically is equal in height to the height of the casing 1 and at its rear side and at the base of the chamber 5 is provided with a water inlet opening 9 tapped for connecting the pipe 10 of the suction line for the pump leading to a cistern, well or water supply source. An open end tube 11 connecting with the base web 10 7 through an opening in the web, longitudinally extends vertically and centrally through and above the chamber 5. The tube 11 as a conduit at its upper end communicates with the chamber 5 and at its lower end with the pump chamber 3, through a horizontal passage 12 formed by the casing 1 and web 7.

The casing 1 and its offset portion 8 has a plane upper surface receiving the apertured division plate 13 with a packing 14 interposed, and upon the division plate a water and air chest or casing 15 is secured, with suitable packing 16 interposed. The casing 15 is of a contour and interiorly subdivided by a partition wall or web 15' to provide a pump discharge chamber 17, an air chamber 18 open to chamber 17 and at an elevation above the water discharge opening 19 in the casing, and an air and priming chamber 20 directly above and open to the chamber 5 in the casing 1 through the port 21 in the division plate and port 22 in the upper face wall of the casing 1. The tube 11 as a water trap 35 for the pump extends upwardly through said ports 21 and 22 into the chamber 20 to a height slightly above the seats of the discharge valves of the pump. The casing 15 above the chamber 20 is provided with an annular flange 23 to provide a cup or funnel leading into the chamber 20 through an opening 24 normally sealed by a screw plug 25. The funnel being of service in initially priming the pump.

45 *Pump details.*—As heretofore asserted the pump in construction may follow any well known principles most suitable for the particular class of service, and preferably including the principles set forth and embraced in the subject matter of Letters Patent #1,166,224 to H. W. Kimes, assignor to The Valie-Kimes Company, dated December 28, 1915. Said patent discloses the suction chambers and discharge chamber of the pump connection by permanently open ports independent of the valve controlled port or ports connecting said chambers.

50 The suction chambers 4—4 of the pump have portions extending downward at opposite sides of the inlet chamber 3 from which they are separated by the partitions or webs 26—26. A piston cylinder 27 is mounted in the partition 26 and has its ends open and communicating with the downwardly extended portions of chambers 4—4 respec-

tively. Mounted in this cylinder is a piston 28 having a piston rod 29 connected thereto. The piston rod 29 passes through a stuffing box in cylinder head plug 30.

55 The chambers 4—4 which are separated one from the other by a vertical partition 31 communicate with the inlet chamber 3, through ports 32—33 respectively in the valve decks 26', these ports being controlled by yielding valves 34—35.

70 The division plate 13 is provided with two ports 36—37 connecting the discharge chamber with the respective chambers 4—4. These ports are controlled by yielding valves 38—39 similar in construction to the 80 valves 34—35.

75 The tube 11 provides a water column for holding back the water in both the suction and discharge chambers of the pump so as to establish water level in the discharge chamber of the pump high enough to submerge or partly submerge the discharge valves, and holds the water normally in the pump against any counterflow through the suction line leaving at all times 90 a priming charge of water in the pump cylinder.

85 The pump in operation lifts the water from its source through a suction line connecting with the inlet to chamber 5, exterior of the tube 11, thence downwardly through tube 11 into passage 12 and chamber 3, from whence, depending upon the direction of piston stroke, it is drawn alternately into the suction chambers 4—4. 100

95 Having described our invention, we claim:

1. In a pump, a casing 1 having a vertical partition 6 and a transverse partition 7 within said casing providing a main water inlet chamber 5 and a pump inlet chamber 3 within the casing, a passage 12 connecting said chambers, a piston cylinder 27 having a piston therein, front and rear suction chambers 4 communicating with the 110 pump inlet chamber, a pump discharge chamber 17, valves controlling the passage between said pump discharge chamber and said suction chambers, and an upwardly extending open ended pipe 11 in said main 115 water inlet chamber 5 to hold a charge of liquid within the pump casing to a height submerging the valve controlled ports connecting the pump discharge chamber 17 and the suction chambers 4.

120 2. In a pump, a casing 1 having an upright partition 6 and a transverse partition 7 extending therefrom to provide an upwardly ranging water inlet chamber 5, a tube 11 mounted in the partition 7 and having an open upper end for the reception of water from the chamber 5, said tube constituting a water trap, a piston cylinder and piston, a suction chamber, a pump discharge chamber, and valve means control- 130

ling the communication between said suction chamber and pump discharge chamber the top of the tube 11 extending to a sufficient height to hold a charge of water with-
5 in the pump casing to submerge the ports connecting the suction and discharge chambers.

3. In a pump, a casing having an upwardly ranging water inlet chamber formed
10 within the main casing of the pump, a tube mounted in the base of said water inlet chamber and having an open upper end for the reception of water from said water inlet chamber, said tube constituting a water
15 trap, a piston cylinder and piston, a suction chamber, a pump discharge chamber and

valve means controlling the communication between said suction chamber and pump discharge chamber, the top of the said tube extending to a sufficient height to hold a 20 charge of water within the pump casing to submerge the ports connecting the suction and discharge chambers.

In witness whereof, we hereunto subscribe our names, as attested by the two 25 subscribing witnesses.

J. HENRY VAILE.
